UNITED STATES PATENT OFFICE

EDWIN E. BARNEY, OF NEW ROCHELLE, NEW YORK, ASSIGNEE TO REMINGTON TYPEWRITER COMPANY, OF ILION, NEW YORK, A CORPORATION OF NEW YORK

TYPEWRITING MACHINE

Application filed November 27, 1928. Serial No. 322,199.

My invention relates to typewriting machines and more particularly to case-shift mechanism therefor.

The main object of my invention, generally stated, is to provide very simply yet highly efficient means whereby the case-shift lock can be released from the right hand, as well as from the left hand, case-shift key.

A further object of my invention is to readily incorporate the features thereof in a Remington portable machine, for example, without materially modifying the existing structural features thereof, and by employing the case-shifting mechanism itself as a means by which the case-shift lock may be released from either the right hand or left hand case-shift key, without the provision of any special case-shift lock releasing means or devices.

To the above and other ends which will hereinafter appear, my invention consists in the features of construction, arrangements of parts and combinations of devices set forth in the following description and particularly pointed out in the appended claims.

In the accompanying drawing, wherein like reference characters indicate corresponding parts in the different views—

Fig. 1 is a fore and aft, vertical sectional view showing sufficient number of parts of a typewriting machine to illustrate my invention in its embodiment therein.

Fig. 2 is a top plan view of the same.

Fig. 3 is a diagrammatic perspective view of the same with parts broken away.

I have shown my invention in the present instance embodied in a Remington portable machine in which said invention may be readily incorporated without materially modifying the structural features of said machine as they now exist. It should be understood, however, that the invention is not restricted to embodiment in such machine but may be employed in typewriting machines generally wherever found available.

The present invention may be said to be an improvement on the construction disclosed in the patent to H. E. Bridgewater, No. 1,442,792, dated Jan. 23, 1923.

In the accompanying drawing the carriage,

designated as a whole by the reference numeral 1, supports a cylindrical platen 2. The carriage is supported by crossed rollers 3 to travel from side-to-side of the machine on a carriage support 4 which constitutes part of a case-shift frame by which the case-shiftable-member or platen carriage may receive a case-shifting movement fore and aft of the machine.

The remainder of the case-shift frame comprises parallel side arms 5 arranged at opposite sides of the machine near the side plates 6 of the frame and which extend longitudinally fore and aft of the machine. The forward ends of these arms are pivoted at 7 to supporting arms or links 8 which in turn are pivoted at 9 to the side plates 6. The rear end portions of the arms 5 are provided with inwardly extending flanges 10 on which is secured the carriage support 4. The rear end of the case-shift frame is supported by parallel arms 11 which are pivoted at their upper ends, at 12, to the carriage support and project upward from and are fixed to a rock shaft 13, mounted at its ends in bearings in the machine frame.

Secured to and extending upward from each of its side arms 5 of the shift frame is a case-shift stop 14 which cooperates with adjustable stops 15 carried by the side plates 6 of the frame to limit the fore and aft case-shifting movements of the case-shift frame and the parts carried thereby.

The key controlled case-shifting devices by which motion is transmitted to the case-shift frame are, in the present instance, as follows:

A slightly flexible rock shaft 16 is mounted at its ends in bearings in the side plates 6 of the frame, such shaft therefore extending throughout the width of the machine. About midway in its length this shaft is provided with an upwardly extending crank arm 17 to which is pivoted, at 18, one end of a case-shift link 19 that has its opposite twisted end pivoted, at 20, to a bracket 21 secured to the carriage support 4.

Near the left hand end of the flexible shaft 16 there is secured a rearwardly extending crank arm 22 provided at its free end portion, and at one side thereof, with an anti-friction

roller 23. A depending projection 24 on a case-shift key lever 25 coacts with this roller 23 to depress the arm 22 and rock the shaft 16 and thereby effect a rearward shift of shift frame and the carriage from the normal, lower-case, position to the upper-case position. The shift lever 25 is pivoted on a fixed pivot rod 26 and carries the usual shift key 27 at its forward end.

10 The case-shift key lever 25 also carries a key controlled case-shift locking-device comprising a lever 28 pivoted at 29 on an upward extension 30 on the lever 25. One arm of the lever 28 carries a key 31 by which it may be turned on its pivot 29 against the force of a spring 32 and by which the lever 25 may be depressed. The other depending arm of the locking lever 25 terminates in a hook-like engaging member 33 which is adapted, on the depression of the key 31, to engage beneath the lower end of a locking device or plate 34. This locking plate is secured at its upper end, as at 35, to the front guide comb or plate 36, secured to the frame of the machine. The locking plate 34 is in the nature of a stiff leaf spring and may have its lower end adjusted fore and aft of the machine, so that it will properly coact with the engaging end of the locking lever 28. The means for effecting this 20 adjustment consists of a headed screw 37 the stem of which passes freely through an off-set opening in the spring plate 34 and at its threaded end is received in coincident openings in the guide comb 36 and in a block 38 secured to the rear of the guide comb to give 30 added thickness thereto at this point.

Springs 39 return the case-shifted parts to normal position, a separate spring 40 being employed to return the case-shift key lever 40 25 to normal position. On the other hand springs 41 act as suspension springs which tend to counteract the downward weight or pressure of the carriage, as disclosed in my Patent No. 1,570,988, dated Jan. 26, 1926.

45 It will be understood that when the carriage is in the case-shifted position, as shown in Fig. 1, the springs 41 exert a slight forward pull on the case-shift frame, as well as an upward pull thereon, and tend to return the 50 case-shift frame and carriage to normal position. It is an important factor of the present invention that the force exerted by the spring 32 shall be greater than that exerted by the spring 40 for reasons which will presently 55 appear.

It will be understood that a depression of the locking key 31 is effective to shift the carriage to the upper case position and bring the stops 14 against the rear arresting stops 15. 60 At the same time the engaging end 33 of the locking lever 25 will be forced beneath the lower end of the locking device 34, and will hold and lock the shift frame and carriage against return movement from the shifted 65 position when the locking key 31 is released.

This effect will be produced notwithstanding the fact that the spring 32 is of greater force than the spring 40. This is due to the reactive force of the springs 39 and 41 and the weight of the case-shift frame and carriage which in addition to the reactive force of the 70 spring 40 are sufficient to overcome the force of the spring 32. It will be understood, however, that as soon as these reactive forces are relieved, then the force of the spring 32 becomes sufficient to turn the locking lever 28 75 to the dotted line position shown in Fig. 3, releasing the engaging end 33 of said lever from the cooperative locking device 34, and permitting the case-shift frame and carriage to return to normal position.

The reactive force mentioned above which holds the locking lever 28 engaged, may be relieved in the usual manner by a depression of the case-shift key 27.

In accordance with my present invention I have provided means whereby the reactive force mentioned above also may be relieved to release the locked case-shift locking-lever by depressing a right hand case-shift key. This may be effected by employing parts of the case-shift mechanism itself, and without the necessity of employing any special releasing devices for this purpose. Such construction will now be described.

At the right hand side of the key board is located a case-shift key-lever 42 pivoted on the pivot rod 26 and having a case-shift key 43. A depending projection 44 on said key-lever is adapted to coact with a roller 45 carried at the free end, and on one side, of a crank arm 46. This crank arm is fixed to the flexible shaft 16 near the right hand end thereof and projects rearward therefrom, like the corresponding crank arm 22 at the other end of the shaft. The case-shift lever 42 is connected to a spring 47 by which it is returned to normal position.

The case-shift key 43, as well as the case-shift key 27, is available to effect a shift of the carriage to upper case position providing a right hand, as well as a left hand, key for this purpose.

Referring more particularly to Fig. 3 it will be understood that when the case-shift locking-lever 28 is engaged, as shown in full lines, downward pressure exerted on the case-shift key 43 is effective to spring the flexible shaft 16 intermediate of its ends, as indicated by a somewhat exaggerated showing in dotted lines in Figs. 2 and 3. This is due to the fact that the depression of the key 43 tends to turn the shaft 16 clockwise, as the parts appear in Fig. 3. The clockwise movement of the shaft on the other hand is resisted at this time by the inflexibility of link 19 and the various parts up to and including the case-shift stops 14 and the rear coacting stops 15. Therefore, the energy exerted to turn the shaft 16 will, at this time, tend to flex 125 it.

the middle portion of the shaft 16 around the pivot 18 as a center and will slightly lower the crank arm 22. The result of lowering the arm 22 as described, is to relieve the reactive force of the springs 39 and 41 and the weight of the parts on the case-shift lever 25 and the locking-lever 28 is carried thereby. When this occurs the force of the spring 32 is sufficient to overcome the force of the spring 40, thereby permitting the locking-lever 28 to be moved by its spring 32 to the dotted line position shown in Fig. 3, releasing the locking-lever from its coacting engaging member 34 and permitting the case-shift frame and carriage to be returned to normal position under the action of the springs 39 etc., when the operator releases the depressed case-shift key 43.

From the foregoing it will be understood that I have provided no special releasing devices operable from the right hand shift key to release the locked case-shift lever, but have employed the case-shift mechanism itself to obtain this result and have modified parts of such mechanism with this end in view. It is of course an important factor that as few parts as possible, consistent with the ends to be attained, be employed, and this is especially true in portable typewriters where of necessity the parts are closely arranged in a comparatively small space and there is but little room to provide for additional parts. Therefore, especially in this class of machines, the present construction becomes highly important.

I have referred herein to the shaft 16 as being slightly flexible to attain the ends in question. In practice I have found that a steel rock shaft made from $\frac{1}{5}$ of an inch stock and unsupported except at its ends against flexing movement answers the purposes of the present invention admirably.

In the present construction I have shown a stop arm 48 secured to a fixed cross bar 49 on the machine frame. The effective portion of this stop arm is located some distance from the rock shaft 16 when the latter is in an unflexed condition, as shown in Fig. 1. When the stop arm is employed it is merely used to limit the extent to which the shaft 16 may be flexed. However, since the case-shift lever 42 has a limited extent of depression, there is not, ordinarily, any occasion to use the stop arm 48 and it may be omitted.

Various changes may be made in the construction without departing from my invention as it is defined in the accompanying claims.

What I claim as new and desire to secure by Letters Patent, is:—

1. The combination of a member mounted for case-shifting movement; and case-shift mechanism therefor including a case-shift key-lever at one side of the machine, a key-actuated case-shift locking-lever carried by

said key-lever, an engaging device cooperative with said locking-lever, a second case-shift key-lever at the opposite side of the machine, a flexible rock shaft extending from side-to-side of the machine, inflexible connections between said rock shaft and the case-shiftable-member, and means on said rock shaft with which said case-shift key-levers coact to rock said shaft, whereby when the case-shiftable-member is locked in the shifted position pressure exerted on said second case-shift key-lever is effective to flex said rock shaft and relieve the reactive force exerted on said case-shift locking-lever enabling it to be released from its coacting engaging device and the case-shiftable-member to be returned to normal position.

2. The combination of a member mounted for case-shifting movement; and case-shift mechanism therefor including a case-shift key-lever at one side of the machine, a key-actuated case-shift locking-lever pivoted to and carried by said key-lever, an engaging device cooperative with said locking-lever, a spring for returning said case-shift key-lever to normal position, a spring for returning said locking-lever to normal position relative to the case-shift key-lever, and of stronger effective force than the returning spring for the case-shift key-lever, a second case-shift key-lever, and case-shifting connections between said case-shift key-levers and said case-shiftable-member, which connections include a flexible rock shaft, a connection from said rock shaft to the case-shiftable-member, and means intermediate said rock shaft and said case-shift key-levers which effect a rocking of the shaft from either case-shift key-lever, whereby when the case-shiftable-member is locked in its shifted position pressure exerted on said second case-shift key-lever is effective to flex said rock shaft and relieve the reactive force exerted on said case-shift locking-lever enabling it to be released from its coacting engaging device and the case-shiftable-member to be returned to normal position.

3. The combination of a member mounted for case-shifting movement; and case-shift mechanism therefor including a case-shifted key-lever at one side of the machine, a key-actuated case-shift locking-lever pivoted to and carried by said key-lever, an engaging device cooperative with said locking-lever, a spring for returning said case-shift key-lever to normal position relative to the case-shift key-lever and of stronger effective force than the returning spring for the case-shift key-lever, a second case-shift key-lever, and case-shifting connections between said case-shift key-levers and said case-shiftable-member, which connections include a flexible rock shaft extending from side-to-side of the machine, an operative connection from a point substantially midway in the length

- of said shaft to said case-shiftable-member, means intermediate said rock shaft and case-shift key-levers that effect a rocking of said shaft from either case-shift key-lever, whereby said rock shaft is flexed by a pressure exerted on said second case-shift key-lever when the case-shiftable-member is locked in shifted position, thereby enabling the reactive force exerted on the case-shift locking-lever to be relieved and effect its release from the coacting engaging device and the return of the case-shiftable-member to normal position to be effected.
4. The combination of a member mounted for case-shifting movement; and case-shift mechanism therefor including a case-shift key-lever at one side of the machine, a key-actuated case-shift locking-lever pivoted to and carried by said key-lever, an engaging device cooperative with said locking-lever, a spring for returning said case-shift key-lever to normal position, a spring for returning said locking-lever to normal position relative to the case-shift key-lever and of stronger effective force than the returning spring for said case-shift key-lever, a second case-shift key-lever, and case-shifting connections between said case-shift key levers and said case-shiftable-member, which connections include a flexible rock shaft extending from side-to-side of the machine, a crank arm on said rock shaft disposed substantially midway in the length thereof, a connecting link between said crank arm and the case-shiftable-member, and crank arms near the ends of said rock shaft with which said case-shift key-levers coact, whereby said rock shaft is flexed by pressure exerted on said second case-shift key-lever when the case-shiftable-member is locked in shiftable position, thereby enabling the reactive force exerted on the case-shift locking-lever to be relieved and effect its release from the coacting engaging device and the return of the case-shiftable-member to normal position to be effected.
5. The combination of a member mounted for case-shifting movement; and case-shift mechanism therefor including a case-shift key-lever at one side of the machine, a key-actuated case-shift locking-lever carried by said key-lever, an engaging device cooperative with said locking-lever, a second case-shift key-lever at the oposite side of the machine, a flexible rock shaft extending from side-to-side of the machine, a crank arm substantially midway in the length of said rock shaft, a case-shift link connecting said crank arm with case-shiftable-member, crank arms on said rock shaft near the ends thereof and with which said case-shift key-levers coact, whereby said rock shaft is flexed by pressure exerted on said second case-shift key-lever when the case-shiftable-member is locked in shifted position, thereby enabling the reactive force exerted on the case-shift locking-

lever to be relieved and effect its release from the coacting engaging device and the return of the case-shiftable-member to normal position to be effected.

Signed at Stamford in the county of Fairfield and State of Connecticut this 26 day of November A. D. 1928.

EDWIN E. BARNEY.
